UNITED STATES PATENT OFFICE.

FRANCIS E. MERRIMAN, OF BOSTON, MASSACHUSETTS, ASSIGNOR TO THE SOVEREIGN GRAND LODGE OF THE INDEPENDENT ORDER OF ODD FELLOWS, OF BALTIMORE, MARYLAND.

DESIGN FOR A BADGE.

SPECIFICATION forming part of Design No. 28,780, dated June 7, 1898.

Application filed March 22, 1898. Serial No. 674,932. Term of patent 14 years.

To all whom it may concern:

Be it known that I, FRANCIS E. MERRIMAN, a citizen of the United States, residing at Boston, in the county of Suffolk and State of Massachusetts, have invented and produced a new and original Design for a Badge, of which the following is a specification, reference being had to the accompanying drawings, forming part thereof.

Figure 1 is a front view of a badge, showing my new design. Fig. 2 is a sectional view on the line $\alpha\alpha$ of Fig. 1.

As shown in the drawings, the leading or material feature of my design consists of a circular base upon which is disposed a regal crown, crossed crook and sword, and three links. The regal crown occupies the upper portion of the circular base and the three links the lower portion. The crook and sword

are partially hidden by the crown, and they cross at a point at or near the center of the base, and their lower portions pass through the middle link. The hilt of the sword projects above the crown at one side of the vertical center thereof, and the crook has its bent or crooked portion projecting above the crown at the opposite side of the vertical center thereof.

Having described my invention, what I claim as new, and desire to secure by Letters Patent, is—

The design for a badge or similar article, substantially as herein shown and described.

FRANCIS E. MERRIMAN. [L.S.]
